ASSIGNORS TO THE NATIONAL SUPPLY COMPANY OF DELAWARE, OF NEW YORK,
N. Y., A CORPORATION OF DELAWARE.

CHAIN-DRIVE SAND-REEL ATTACHMENT.

Application filed October 4, 1926. Serial No. 139,468.

This invention relates to chain drive sand reel attachments and is more particularly directed to an attachment adapted to be mounted upon a sand reel shaft for driving 5 the same through a chain drive mechanism from the band wheel shaft, such as forms a part of standard and combination standard and rotary drilling rigs.

In the standard well drilling rig as customarily constructed, the sand reel is placed 10 in the derrick between the engine and the band wheel with its shaft substantially parallel to the shaft of the band wheel. In drilling operations, the sand reel is used to 15 wind up or pay out the sand line. The sand line is used primarily to handle the bailer and for certain other auxiliary drilling operations. These operations, especially those 20 of handling the bailer, require the provision of means to secure great flexibility in the handling of the sand line. It must be capable of allowing the bailer actuated solely 25 by its own weight to run freely into the hole at great speed, and yet be always under perfect control. Such braking means must be 30 provided that the descending bailer can be quickly brought to a stop at any point and yet so gradually as not to cause any jar or shock which would tend to break the sand line.

In filling the bailer, and in such operations as measuring and marking the depth 35 of the hole on the sand line, the sand reel must be provided with means by which it can be easily and conveniently handled so 40 that the bailer can be alternately raised and lowered without "grabbing". This provision is necessary to enable the driller to determine or judge by the "feel" of his operating device just what is taking place in the hole.

In the drilling rigs as used at the present time, this delicate yet positive control of the sand reel has been accomplished by mounting 45 the bearings of the sand reel shaft in such manner that at one end it can be swung forward and back from a neutral position by means of the knuckle-post. In its neutral position, the sand reel is entirely disconnect- 50 ed by the driving and braking means and is free to rotate and thus to respond to any pull on the sand line. This allows the bailer or any other weight attached to the sand line to run freely into the hole.

When the knuckle post is swung forward, a friction wheel mounted on the sand wheel 55 shaft is moved forward into frictional contact with the face of the revolving band wheel. By this means, the sand reel is so rotated as to wind up the sand line and to raise whatever is attached thereto. When 60 the knuckle post is swung to the rear of the neutral position, the friction pulley is brought into frictional contact with the back 65 brake by means of which the rotation of this sand reel in either direction is restrained. The motion of the knuckle post is controlled by a single lever manipulated by the driller and which is conveniently positioned just forward of the Samson post from which point all drilling operations are controlled 70 in the standard rig.

One of the greatest difficulties incident to the use of this sand reel assembly as above set forth, lies in the fire hazard created by the same, due to the frictional driving contact of the driving wheel shaft and the frictional braking against a wooden post of arresting the rotation of the same. 75

Another great disadvantage of this assembly lies in the great strain placed upon the 80 bearings within which the sand reel shaft is journaled so that the same quickly wears and must be frequently replaced or repaired.

Many times standard rigs have been constructed and are now in use in which the sand reel assembly, such as that previously described, is employed, and it is an object of this invention to provide an attachment which may be mounted upon the sand reel shaft by rigidly securing the free or floating 85 bearing thereof in place to a post on the derrick, and which attachment is adapted to be driven by a chain drive from the band wheel shaft, and in which attachment there is provided clutch means for releasably 90 clutching the drive from the band wheel shaft to the sand reel shaft so that the same will be released to permit the free rotation of the sand reel to allow the free play of the sand line, and in 100 which attachment means are provided for braking the rotation of the sand reel shaft when it is desired to arrest winding up or paying out of the sand line.

Another object of this invention is to 105 provide an attachment adapted to be mount-

ed upon the sand reel shaft as customarily mounted in an employed in standard drilling rigs and which attachment is so constructed that the same may be mounted in either position so that the same is driven from either side of the band wheel shaft, depending upon the particular conditions found in each individual drilling rig as to space for permitting the mounting of the driving sprocket upon the band wheel shaft and the locating and positioning of the attachment.

Another object of this invention is to provide an attachment for a sand reel shaft, which attachment comprises within itself a complete operative unit which may be mounted upon the sand reel shaft by merely sliding the same over the shaft and securing the same thereto, and which attachment includes a sleeve or quill shaft upon which a driving sprocket is loosely journaled and on which quill shaft clutch means, preferably of the friction type are mounted for releasably engaging the driving sprocket with the said quill shaft and operably connected with which clutch means, brake means are provided, and which attachment includes as an integral part of the assembly thereof clutch and brake actuating means which are operably connected with a single operating lever which may be connected to the customary rods to the operating lever mounted in the floor of the drilling rig in advance of the Samson post so that on actuation of the operating lever in the rig in one direction, the clutch is engaged to drive the sand reel shaft and on actuation of the operating lever to the opposite position, the clutch is released and braking means are applied.

Other objects and advantages of this invention will be apparent from the following detailed description of a preferred embodiment thereof as illustrated in the accompanying drawings, in which drawings

Figure 1 is a top plan diagrammatic view of the standard rig illustrating a sand reel attachment as embodying this invention as mounted upon the sand reel shaft, the derrick of the rig being broken away to illustrate the respective positions of the hole, Samson post, and the control lever of the sand reel attachment.

Figure 2 is an enlarged fragmental elevation, illustrating the sand reel attachment embodying this invention as mounted upon the sand reel shaft.

Figure 3 is an end elevation partly in section and taken substantially on the line 3—3 of Figure 2, showing a preferred manner of slidably securing the quill shaft to the sand reel shaft.

Figure 4 is a central sectional side elevation of the sand reel attachment embodying this invention.

In the preferred embodiment of this in-

vention, illustrated in the accompanying drawings, 1 illustrates a derrick mounted on the usual mud sills 2. 3 indicates a primary source of power of any suitable form, such as a steam engine, gas engine, electric motor, or the like, mounted on the sills 2.

The engine 3 drives the band wheel 4 mounted upon the band wheel shaft 5 which carries the crank 6. The crank 6 has a plurality of bolt holes (not shown) formed therein so that the crank arm or walking beam may be connected along the length to vary the stroke of the well pump as desired. The customary drive from the engine 3 to the band wheel 4 is through a belt 7. The Samson post 8 supports customarily the walking beam (not shown). The well hole is illustrated at 9. The sand reel 10 with its flanges 11 is mounted upon the shaft 12. The shaft 12 is journaled at its ends in suitable bearings 13 and 14 secured to the sills 2 in any suitable or desirable manner. The bearing 13 is customarily the loosely mounted bearing upon which the sand reel shaft 12 is rocked by means of the knuckle post (not shown), customarily provided. The bearing 13, in accordance with this invention, is fixed to the post 15 and the attachment embodying this invention is mounted on the shaft 12 which is then rigidly mounted in position.

Mounted upon the shaft 12 is a sleeve or quill shaft 16 which is secured to the shaft 12 by any suitable means, such as by a key 17.

Journaled upon a bearing 18 mounted upon the quill shaft 16 is a clutch and sprocket hub 19. Secured to the end of the quill shaft 16 is a retaining disc 20 for maintaining the hub 19 in position upon the said shaft. Secured to the hub 19 is a sprocket 21.

Mounted upon the band wheel shaft 5 in alignment with the sprocket 21 is a second sprocket over which the band wheel shaft sprocket and sprocket 21 a chain 22 is trained for driving the sprocket 21 from the band wheel shaft 5.

Clutch means are provided for releasably engaging the sprocket 21 with the quill shaft 16, which means are preferably of the friction type and are of the following construction:

Cast integral with the hub 19 is a flange 23, which flange 23 has a transversely extending circumferential flange 24 formed at its periphery. Formed integral with the flange 24 or preferably formed as an independent part because of ease in assembling and taking down is a split clutch drive-ring 25, which split clutch drive-ring 25 is provided with lagging 26 at its opposite sides.

Splined or otherwise slidably secured to the quill shaft 16 is a hub 27. Mounted on the shaft 16 intermediate the hub 27 and the hub 19 is a clutch spider 28. Mounted on the opposite sides of the clutch drive-ring 25 are inner and outer plates 29 and 30.

Means are provided for releasably securing the plates 29 and 30 with the lag sides of the clutch drive-ring 29, which means are preferably of the following construction:

Formed integral with the spider 28 is a flange 31 through which flange 31 a plurality of clutch drive pins 32 are passed. The clutch drive pins 32 are provided at one end with enlarged heads 33 upon which the outer plate 30 is slidably mounted. Driving bushings 34 are mounted upon the driving pins 32 on the opposite side of the drive-ring 25 and mounted upon the driving bushing 34 is the inner plate 29. Interposed in complementary bores formed in the plates 29 and 30 are compression springs 36 which operate to normally expand the engaging plates 29 and 30 away from the clutch drive-ring 25.

Formed integral with or secured to the outer plate 30 are arms 37, which arms 37 are pivotally secured at pins 38 to one end of the toggle links 39, which toggle links 39 are pivotally secured at pins 40 to links 41, which links 41 are pivotally secured at pins 25 42 to the hub 27.

Formed on the toggle links 39 are bosses 43, in which bosses 43 studs 44 are screw-threaded so as to engage at their inner ends the outer periphery of the inner plates 29. The engagement of the studs 44 with the inner plates 29 may be adjusted by screw-threading the studs 44 into the bosses 43 and a lock nut 45 is provided for locking the adjustment.

Formed integral with or secured to the flange 28 is a brake rim 46, upon which brake rim 46 a brake band 47 is mounted. Means are provided for actuating the brake band 47 to engage the same with the brake rim 46 and for engaging and disengaging the plates 29 and 30 with the clutch drive ring 25, which means are preferably of the following construction:

A channel iron 48 is secured to the mud sills 2 by any suitable or desirable means and a bolt 49 is secured to an angle iron 50 which is secured to the channel iron 48 and is passed through an eye 51 secured to the dead end of the brake band 47. Means are provided for adjustably securing the bolt 49 to the eye 51, which means are indicated at 52.

Journalized in bearings 53 secured to the channel iron 48 is a rock shaft 54 which is secured as illustrated at 55 to the live end of the brake band 47. The rock shaft 54 is bent to form or is secured to an actuating lever 56, which actuating lever 56 is secured to a rod 57 which extends forward of the drill rig and is secured to a rock shaft 58 which is at its opposite end provided with an operating lever 59 which is mounted in position in the derrick 1 in advance of the Samson post 8.

Secured to the rock shaft 54 is a mitre gear 60, which mitre gear 60 meshes with

a mitre gear segment 61 which is formed integral with or secured to an operating link 62, which operating link 62 is secured to a rod 64. The rod 64 is adjustably secured by means of an adjustable U-bolt connection 65 79 to a link 66, which link 66 is secured to the clutch actuating fork 63. The U-bolt connection is adjustable by means of a set-screw 67 held in position by means of a lock-nut 68. This adjustable means of connecting 75 the gear 61 with the clutch actuating fork 63 permits the same to be easily adjusted so that the clutch will be actuated or released when the brake is released or applied and also permits adjustment to compensate for 80 wear of the brake band.

It will be obvious from the foregoing that as the operating lever 56 is actuated from the operating lever 59 that the clutch plates 29 and 30 will be engaged with the clutch driving ring 25 as the brake rim 47 is released from engagement with the brake rim 46 and that on actuation of the lever 56 in a reverse direction, the brake band 47 will be engaged with the brake rim 56 as the plates 29 and 30 are disengaged from driving contact with the clutch driving ring 35.

The quill shaft 16 is mounted on the shaft 12 so that the same may be easily slid to any desired position relative to the band wheel 95 4 and for this purpose I prefer to provide a plurality of bolts 69 which have segmental cylindrical cutouts 70 which are formed to the curvature of the shaft 12. The bolts 69 are mounted in bores 71 formed in bosses on 100 the quill shaft 16 so that the cutouts 70 bear against the shaft 12 when the nuts 72 are screw-threaded to the said bolts 69. This construction also permits the quill shaft to be formed in one piece and not split and 105 permits the use of a straight feather driving key 17 rather than a tapered driving key.

Having fully described a preferred embodiment of our invention, it is to be understood that we do not wish to be limited to 110 the exact details of construction herein set forth, which may obviously be varied without departing from the spirit of our invention as set forth in the appended claims.

I claim:

1. In a sand reel attachment, the combination of a quill shaft, means for securing the quill shaft to the sand reel shaft of an oil well rig, a sprocket journaled on the quill shaft, a clutch hub splined on the quill 120 shaft, clutch means interposed between the clutch hub and said sprocket for releasably engaging the sprocket with the said quill shaft, a brake rim mounted on one of the elements of the said clutch means, and a brake band mounted on the brake rim.

2. In a sand reel attachment, the combination of a shaft, a sand reel secured to the shaft, a quill shaft secured to the said shaft, a sprocket journaled on the quill shaft,

clutch means for releasably engaging the sprocket with the said quill shaft, and brake means mounted upon one of the elements of the said clutch means.

5. In a sand reel attachment, the combination of a quill shaft, a sprocket slidably mounted on the shaft, a hub splined to the said quill shaft, a hub journaled on the shaft, means secured to the said hub for holding a 10 clutch ring of a clutch, a spider journaled on the said quill shaft intermediate the splined hub and the journaled hub, an inner clutch plate and an outer clutch plate, means secured to the said spider and adapted to be actuated from the splined hub for 15 engaging the inner and outer plates with the said clutch ring, and braking means mounted on the said spider.

4. In a sand reel attachment, the combination of a quill shaft, a sprocket journaled on the quill shaft, clutch means for releasably engaging the sprocket with the said quill shaft, brake means mounted upon the elements of the said clutch means, clutch actuating 20 means, brake actuating means, and means for securing the clutch actuating and brake actuating means to a common actuating rod so that on movement of the rod in 25

one direction the clutch is engaged and the brake disengaged.

5. In a sand reel attachment, the combination of a shaft, a sand reel secured to the shaft, a quill shaft, means for slidably securing the quill shaft to the sand reel shaft, a 30 sprocket journaled on the sand reel shaft, a clutch means for releasably engaging the sprocket with the said quill shaft, and brake means mounted upon one of the elements of the said clutch means.

6. In combination with a sand reel shaft 40 having a sand reel secured thereto, of an attachment comprising a quill shaft, a plurality of bolts having cutouts formed to approximately the curvature of the said shaft mounted in bores formed in bosses on the 45 said quill shaft, a feather driving key between the shaft and said quill shaft, clutch means mounted on the said quill shaft, drive means operably connected with the said clutch means, and braking means mounted 50 upon one of the elements of the said clutch means.

Signed at Torrance, California, this 24th day of September, 1926.

EDWARD TIMBS.
LEWIS E. ZERBE.
